UNITED STATES PATENT OFFICE

HARRY A. BAUMAN, OF AKRON, OHIO, ASSIGNOR TO THE B. F. GOODRICH COMPANY,
OF NEW YORK, N. Y., A CORPORATION OF NEW YORK

DESIGN FOR A BATHING CAP

Application filed February 4, 1930. Serial No. 34,400. Term of patent 14 years.

To all whom it may concern:

Be it known that I, HARRY A. BAUMAN, a citizen of the United States, residing at Akron, in the county of Summit and State of Ohio, have invented a new, original, and ornamental Design for a Bathing Cap, of which the following is a specification, reference being had to the accompanying drawing, forming a part thereof.

Fig. 1 is a side elevation of a bathing cap showing my design. Fig. 2 is a transverse section of the same as viewed from the right of Fig. 1.

I claim:

The ornamental design for a bathing cap as shown.

HARRY A. BAUMAN.
